UNITED STATES PATENT OFFICE.

WALTER EVERETT MOLINS, OF LONDON, ENGLAND.

PACKET-MAKING MACHINE.

1,114,281.

Specification of Letters Patent.

Patented Oct. 20, 1914.

Application filed March 13, 1913. Serial No. 754,104.

To all whom it may concern:

Be it known that I, WALTER EVERETT MOLINS, a citizen of the United States of America, residing in London, England, have invented certain new and useful Improvements in Packet-Making Machines, of which the following is a specification.

Hitherto in the making of packets or cartons having one end left open for the introduction of the goods it has been customary to employ a blank which has been, prior to its presentation to the folding or forming mechanism, cut or incised by means of dies or other suitable means so as to form the necessary flaps for closing the open end of the said carton after the contents have been inserted. This method, however, is in practice found to give rise to considerable trouble as the dies require constant attention in order to keep them in a good condition for cutting. With blanks such as these, moreover, it has been found that there is a considerable waste owing to the fact that a slight displacement of the said blank with respect to the members which are required to operate upon it will cause either the malformation of the said carton, or the destruction of the blank, which in either case is wasted.

The present invention has for its object to overcome the aforesaid disadvantages, and in order that this may be effected I employ an unincised blank and arrange for the cutting and scoring thereof to take place while upon the former, or plunger, and at a period when the said blank has been sufficiently engaged by the forming mechanism to prevent its displacement.

In order that the invention may be the better understood drawings are appended in which:—

Figure 1 is a front elevation of the machine embodying the present invention. Fig. 2 is a side elevation partly in section of the scoring mechanism. Fig. 3 is a sectional plan showing the radially moving cutting blades. Fig. 4 is a detail sectional view on an enlarged scale showing the operation of the scoring devices. Fig. 5 shows the class of packet produced by the machine.

Referring to the accompanying drawings in which the invention is illustrated as applied to a machine having a plunger with which coöperate folding means such as that described in my prior U. S. application Serial Number 670,137 filed January 9,

1912, *a* indicates the plunger which is operatively associated with a rod *a*¹ operated in any convenient manner to effect the vertical reciprocation of the said plunger. Pivotally mounted in brackets are parts *b* each of which is provided with a pair of cutting blades *c*. The blades *c* are spaced a distance apart equal to the width of the plunger. Attached to the spindles *b*⁴ of each of the parts *b* are arms *b*³ which arms are arranged in the path of a projection *d* adjustably secured upon the aforesaid rod *a*¹ in Figs. 1, 2 and 3. By this means when the plunger descends the projection *d* will engage the arms *b*³ and cause the blades *c* to move through an arc of a circle, the direction of which is indicated by the arrows *x*, Fig. 1, the parts *b* acting to turn the blank upward against the sides of the former. Secured to the frame *e* of the machine at a point above the table *e*¹ upon which the blank is placed in order to submit it to the action of plunger *a* are brackets *f* each of which is provided with two downwardly extending fixed blades *f*¹ which blades coöperate with the aforesaid movable blades *c* to incise the upper edges of the blank when it has been turned up on each side of the plunger *a*, so that the packet *w* when finished will, as shown in Fig. 5, have at the open end, or mouth, four flaps such as *w*¹. To facilitate the turning of the flaps *w*¹ over, in order to close the packet, I may provide means for scoring the packet inside along the base of the side flaps, Fig. 5. This scoring operation is effected by means of projections which may comprise plates *g* with knife edges *g*³ secured upon each side of the plunger, as shown in Fig. 4, and which plates project slightly beyond the general plane of the surface of the sides of the plunger at their lower edges.

Coöoperating with the plates or knives just described are hardened plates *g*⁴ disposed as shown in Fig. 4, which plates project somewhat into the path of the plates *g* so that the edges *g*³ of the said plates press against plates *g*⁴ and indent or score the blank at the base *w*² of the flaps. The plates *g*⁴ are secured to the brackets by screws, as shown in Fig. 4, and may have their edges slightly rounded, as shown. The upper ends of plates *g* are sunk flush with the plunger, but the recess *g*⁵ for the blades is deeper as shown, the result being that when pressure is exerted on the scoring edge the blades are

allowed a certain clearance for springing in. The edges of plates g come into action immediately they contact with the hardened parts g^1 . The final folding is effected by 5 the tilting and fixed folders indicated respectively by j and j^1 .

h indicates plates whereby the packet is stripped off the former on the upward movement of the plunger. Instead of operating 10 the movable blades c from the rod a^1 they may be operated from the plunger a , by means of projections b^5 .

Having now particularly described and ascertained the nature of my said invention, 15 and in what manner the same is to be performed, I declare that what I claim is:—

1. In a packet making machine, the combination with a plunger on which the packets are formed, and means for folding 20 packet blanks over said plunger, of coöperating fixed and movable cutters for slitting each partly folded blank to form flaps for closing the mouth of the packet.

2. In a packet making machine, the combination with a plunger on which the packets are formed, and means for folding 25 packet blanks over said plunger; of fixed cutters and coöperating swinging cutters operated by the plunger mechanism for slitting each partly folded blank to form flaps for closing the mouth of the packet.

3. In a packet making machine, the combination with a plunger on which the packets are formed, and means for folding 35 packet blanks over said plunger, of fixed cutters and coöperating movable cutters mounted on said folding means for slitting each blank after the same has been partly folded to form flaps for closing the mouth of the packet.

4. In a packet making machine, the combination with a plunger on which the packets are formed, and a swinging means 45 for folding packet blanks over said plunger, of fixed cutters, and coöperating movable cutters secured to said swinging folding means for slitting each blank after partly folding the same to form flaps for closing the mouth of the packet.

5. In a packet making machine, the combination of a frame, a plunger on which the packets are formed, and a swinging means operated coincident with the descent of the plunger for folding packet blanks over said 55 plunger, of fixed cutters secured to the said frame, and movable cutters mounted on said swinging folding means to coöperate with the fixed cutters for slitting each blank after being partly folded to form flaps for closing the mouth of the packet.

6. In a packet making machine, the combination with a plunger on which the packets are formed and a swinging member pivoted on each side of the path of movement of said plunger to partly fold a blank 65

around said plunger, a pair of fixed cutters on each side of said plunger, and a pair of cutters mounted on each of said swinging folders to coöperate with said fixed cutters for slitting each blank after partly folding 70 the same to form flaps for closing the mouth of the packet.

7. In a packet making machine, the combination with a plunger on which the packets are formed and means for folding 75 packet blanks over said plunger, of fixed means, and movable means carried by the plunger at a point removed from its end and coöperating with the fixed means for forming transverse scores in the sides of the packet near the open end thereof. 80

8. In a packet making machine, the combination with a plunger on which the packets are formed and means for folding 85 packet blanks over said plunger, of spring plates each fixed at one end to the side of the plunger and provided with a projecting rib near its free end, and fixed means adapted to coöperate with the ribs of said spring plates for transversely scoring said 90 packet near the open end thereof.

9. In a packet making machine, the combination with a plunger on which the packets are formed, and means for folding the packet blanks over said plunger, of coöperating fixed and movable cutters for slitting each partly folded blank to form flaps for closing the mouth of the packet, and means on the plunger for transversely scoring 95 said flaps.

10. In a packet making machine, the combination with a plunger on which the packets are formed, and means for folding packet blanks over said plunger, of fixed 100 cutters and coöperating swinging cutters operated by the plunger mechanism for slitting each partly folded blank to form flaps for closing the mouth of the packet, and means on said cutter for transversely scoring the lower ends of the flaps. 105

11. In a packet making machine, the combination with a plunger on which the packets are formed, and means for folding packet blanks over said plunger, of coöperating fixed and movable cutters for slitting each partly folded blank to form flaps for closing the mouth of the packet, spring 110 means carried by said plunger, and fixed means coöperating with said spring means for transversely scoring the flaps at their lower ends. 120

12. In a packet making machine, the combination with a plunger on which the packets are formed, and means for folding packet blanks over said plunger, and a 125 swinging means for folding packet blanks over said plunger, of fixed cutters, and coöperating movable cutters secured to said swinging folding means for slitting each blank to form flaps for closing the mouth of 130

the packet, spring plates carried by said plunger and each provided with a projecting rib near its free end, and fixed means adapted to coöperate with the ribs of said 5 spring plates for transversely scoring said flaps.

In witness whereof I have hereunto affixed my signature in the presence of the

undersigned witnesses this twenty-second day of February in the year of our Lord 1913.

WALTER EVERETT MOLINS.
